UNITED STATES PATENT OFFICE.

CHARLES ADAMS BUSH, OF CORRY, PENNSYLVANIA.

MOTOR.

No. 832,592.

Specification of Letters Patent.

Patented Oct. 9, 1906.

Application filed December 29, 1903. Renewed January 15, 1906. Serial No. 296,154.

To all whom it may concern:

Be it known that I, CHARLES ADAMS BUSH, a citizen of the United States, residing at Corry, in the county of Erie and State of Pennsylvania, have invented a new and useful Motor, of which the following is a specification.

This invention relates to certain improvements in air and gas engines, and has for its principal object to provide improved mechanism for utilizing the force resulting from the explosions of gas or gaseous compounds to create and maintain uniform power, and in this connection a further object of the invention is to effect steady and uniform movement of the parts by lessening to some extent the direct force of the explosion on the piston or similar movable elements to be actuated.

A further object of the invention is to provide a mechanism in which a single piston guided within a single cylinder serves at one end of the cylinder as a pumping apparatus for the compression of air, and at the opposite end of the cylinder the piston is actuated by the explosion of the gas or other fuel.

A further object of the invention is to provide improved means for governing the speed of the engine, the supply of fuel being automatically regulated in order to vary the action of the air-pump and maintain uniform pressure of air in an air-containing reservoir.

With these and other objects in view, as will hereinafter more fully appear, the invention consists in the novel construction and arrangement of parts hereinafter described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a sectional plan view of a power plant, including an air and a gas engine, constructed in accordance with the invention. Fig. 2 is a transverse sectional elevation on the line 2-2 of Fig. 1, illustrating the construction of the explosive-chamber. Fig. 3 is a transverse sectional elevation of the air-engine on the line 3-3 of Fig. 1. Fig. 4 is a detail sectional view of the air-engine valve on the line 4-4 of Fig. 3. Fig. 5 is a transverse sectional view of the valve for controlling the flow of the explosive compound on the line 5-5 of Fig. 1.

Similar numerals of reference are employed

to indicate corresponding parts throughout the several figures of the drawings.

In the drawings, 1 indicates a cylinder provided with an air-jacket 2, into which air flows through a pipe 3, the heated air being exhausted through a pipe 4 and led to a heating system in a building or vehicle in order that the waste heat of the engine may be utilized in cold weather. In addition to this the cylinder is provided with an exhaust-port 5, arranged approximately at the limit of outstroke of the piston, and through this port the products of combustion from the explosion escape and pass through a pipe 6, that connects with the pipe 4, the heated gases and air mingling together and passing to the heating system. Within the cylinder is arranged a double piston 7, comprising a pair of disks having the usual packing-rings and connected together by a plurality of bolts 8, and to this piston is also secured a piston-rod 9, that extends through a stuffing-box at the crank-shaft end of the cylinder and is connected by pitman 10 to a wrist-pin carried by a crank or crank-disk on a vertically-mounted shaft 11. The shaft 11 is stepped in a suitable bearing, and on said shaft is secured a balance-wheel 12, revoluble in a horizontal plane with a view of minimizing friction, the frictional wear occurring at the lower end of the shaft in place of the wear at the end bearings of a horizontal shaft, as usually found in engines. The crank-shaft end of the cylinder is provided with an air-inlet pipe 14 and an air-outlet pipe 15, suitable check-valves being introduced in order to prevent movement of the air in the wrong direction, and at the mouth of the air-inlet pipe is arranged a screen or screens 16 to prevent the entrance of foreign matter to the cylinder. At the back stroke of the piston air is sucked in through the pipe 14, and on the forward stroke this air is forced through the pipe 15 to a suitable compressed-air reservoir 17, more particularly referred to herein-after. The outer end of the cylinder communicates with an explosion-chamber 19, that is formed of very heavy metal in order to resist the force of the explosion, and between the explosion-chamber and the cylinder proper is a partition 20, provided with a number of openings 21, through which the exploded gases may pass to act expansively and with uniform pressure on the whole area of the piston. By this arrangement the piston is not subjected to sudden shock at the

moment of explosion and the resultant jerky action of the engine is prevented, while the exploded gases may readily pass through the openings 21 and act expansively on the piston, so that the pressure will be fully utilized.

The compressed-air reservoir 17 is located adjacent to the cylinder, and to it is connected a governing device comprising a cylinder 24, in which is arranged a movable piston 25, normally held in one direction by a spring 26, the spring being of a strength proportioned to the pressure desired.

The apparatus may work at any pressure, and the stress of the spring may be accurately adjusted by means of a suitable screw 27, carried by a plate or cross-bar and bearing against one end of the spring. The piston 25 is connected to one end of a pivoted lever 28, that in turn is connected to a slidable piston-valve 30, controlling the amount of air and gas or other fuel fed to the explosion-chamber, so that when the pressure of air in the reservoir is excessive the quantity of fuel will be correspondingly reduced, and vice versa.

The valve 30 is carried by a stem 31; that is connected at 32 to the lever 28. The valve is movable longitudinally within a rotary valve 33, mounted in a valve-casing 34, adjacent to the explosion-chamber. The valve 33 is provided with a port 35, which may be turned into alignment with a pipe 36, leading to the explosion-chamber in order to convey the explosive mixture to the chamber, and in this pipe is connected a check-valve in order to prevent back-firing. The casing is further provided with two ports 37 and 38, one of which may be placed in communication with a gasoline-supply tank 39, while the other communicates with the compressed-air reservoir through the medium of a pipe 40. The rotary valve is oscillated in order first to place the port 37 in communication with the gasoline-supply tank, and the liquid gasoline flows thereinto, after which the valve is oscillated to place the port 35 in communication with pipe 36 and the port 38 in communication with the air-supply pipe 40. The compressed air from the reservoir then flows through the port 38 to the valve and forces the gasoline through the pipe 36 into the explosion-chamber, a sufficient quantity of air being admitted to form an explosive compound. The rotary valve is provided with a stem 41, which extends to the exterior of the valve-casing and is provided with an arm 42. This arm is connected by a link 43 to a lever 44, one end of which is pivoted to the supporting-frame of the mechanism.

The shaft of the balance-wheel carries a cam 45, which actuates the lever 44 and determines the extent of movement of the valve 33 to shut off the supply of fuel and allow

compressed air to flow from the reservoir 17 to the pipe 40 to mingle with the gasoline or any other form of liquid or gaseous fuel and passes through opening 35 and pipe 36 into the combustion-chamber. Spring 46 is connected to lever 44 and serves to move arm 42 and turn the valve to admit fuel and shut off air. The flow of fuel is uninterrupted except when shut off by the cam. Then the compressed air passes momentarily through valve 33 into the combustion-chamber 20, carrying with it the fuel. When the piston 25 is exposed to air under heavy pressure, the piston-valve 30 is moved farther into the rotary valve, and the effective area of the ports 37 and 38 is decreased, the ports being closed to a greater or less extent in order to control the admittance of air and fuel.

The construction of the governing mechanism is such as to provide for the most delicate regulation of the quantity and quality of the explosive mixture. When the pressure of air in the reservoir is little, a full charge of fuel and a full volume of compressed air are admitted to the valve, while at maximum pressure of air both the supply of fuel and air would be cut off.

The air in the reservoir 17 is utilized in an air-engine 50, comprising a cylinder 51, having a piston 52, that is connected in the usual manner to a crank-shaft 53, mounted in suitable bearings and provided with the usual balance or belt wheel 54. To the cylinder is secured a chest 55, provided at its opposite ends with cylinder-ports 56 57, and at the center is a port 58, in communication with the air-reservoir through the medium of a pipe 59. In the pipe 59 is a throttle-valve 60 under the control of the governor 61, that receives motion from a movable portion of the engine. At a point opposite the air-entrance port is an exhaust-port 63, that is connected by the pipe 3 to the air-jacket of the explosion-chamber, the exhaust-air of the engine serving to cool the cylinder of the explosion-chamber and when heated being further utilized in the heating of a building or vehicle, as previously described.

In the valve-chest is mounted a revoluble valve 63', cylindrical in form and divided by a transverse partition 64 into two compartments, one of which communicates with the air-entrance port and the other with the exhaust-port. This valve is mounted on ball-bearings 66 in order to lessen friction, and at the top of the valve is a bevel-gear 67, intermeshing with a gear 68, that is connected by a shaft 69 and miter-gearing 70 to the crank-shaft of the engine. The gearing is so proportioned that at each half-revolution of the shaft the valve will receive half a revolution. From each of the compartments of the valve leads a port 71, and the ports are so arranged that while air is flowing into one end of the cylinder through one port it will be exhaust-

ing from the opposite end of the cylinder through the other port. In some cases the exhaust-port may be of larger size than the air-entrance port, so as to permit of the 5 quicker exhaust of the air, and thus prevent any tendency to back pressure, or the port may be smaller in order to maintain an air-cushion to relieve the movement of the piston. The construction is such as to permit 10 of the arrangement of the valve as circumstances may dictate and to gain any or all of the advantages of the ordinary slide-valve. The balance-wheel of the explosion-engine is provided with a handle by which the engine 15 may be manipulated by hand in order to supply the reservoir 17 with a quantity of air under pressure in starting the apparatus into operation.

With a device constructed in the manner 20 described it is possible to provide for steady and uniform movement, and while the power plant may be of any size and capacity and utilized for any purpose it is especially adapted for the propulsion of launches or automobiles, 25 inasmuch as it requires little or no attention on the part of the operator and is at all times under thorough control, so that the speed may be properly regulated in accordance with the load and only so much fuel consumed as may be absolutely necessary to produce the desired force.

Having thus described the invention, what is claimed is—

1. In mechanism of the class described, an 35 internal-combustion engine, including a cylinder having at one end an inlet and an escape for the explosive mixture, and at the opposite end an air-inlet and an air-outlet, a piston arranged within the cylinder, a compressed-air reservoir connected to the air-outlet, a regulating-valve for the explosive mixture, a piston or plunger constantly exposed to the air-reservoir pressure and connected to said regulating-valve and varying 45 the position of the same in accordance with the pressure within the reservoir, an air-driven engine connected to the reservoir, and means for governing the quantity of air passing from the reservoir to said air-driven engine. 50

2. In mechanism of the class described, an explosion-engine including a cylinder and explosion-chamber, an air-pump, a reservoir fed from the pump, a revoluble inlet-valve leading to the explosion-chamber, means for 55 rotating the valve, and a slidable valve disposed within the rotary valve and controlled by the pressure of air in the reservoir.

3. In mechanism of the class described, a 60 valve-casing communicating with the explosion-chamber of an engine, a compressed-air reservoir also in communication with the casing, a fuel-supply pipe also communicating with the casing, a hollow valve arranged within said casing and movable to receive the 65 fuel and to place the compressed-air reservoir in communication with the explosion-chamber, a controlling-valve arranged within the hollow valve, a piston or plunger exposed to the pressure of air in the reservoir, and means 70 for connecting said piston or plunger to said controlling-valve.

4. In mechanism of the class described, a 75 valve-casing in communication with the explosion-chamber of an engine, a compressed-air reservoir also in communication with the casing, a fuel-supply pipe communicating with the casing, a valve arranged within the casing, a cylinder in communication with the reservoir, a piston disposed in the cylinder, an adjustable spring tending to move the piston against the air-pressure, and means connecting the pistons to the valve. 80

5. In an apparatus of the class described, a 85 gas-engine of which a portion forms an air-pump, a compressed-air reservoir fed from the pump, a valve for controlling the passage of explosive compound to the engine, means controlled by the pressure of air in the reservoir for adjusting said valve, and an air-pressure-operated engine connected to said reservoir, substantially as specified. 90

In testimony that I claim the foregoing as my own I have hereto affixed my signature in the presence of two witnesses.

CHARLES ADAMS BUSH.
